DESIGN FOR A TOY AUTOMOBILE

George E. Elliott, Birmingham, Ala.

Application April 4, 1945, Serial No. 118,857

Term of patent 3½ years

(Cl. D34—15)

To all whom it may concern:

Be it known that I, George E. Elliott, a citizen of the United States of America, residing at Birmingham, in the county of Jefferson and State of Alabama, have invented a new, original, and ornamental Design for Toy Automobile, of which the following is a specification, reference being had to the accompanying drawing, forming part thereof.

The figure is a perspective view of a toy automobile, showing my new design.

I claim:

The ornamental design for a toy automobile, as shown.

GEORGE E. ELLIOTT.
